[57] CLAIM

The ornamental design for a conformal antenna for a satellite dish, as shown and described.

DESCRIPTION

FIG. 1 is a front left side perspective view of a conformal antenna for a satellite dish showing our new design;

FIG. 2 is a rear elevation view thereof;

FIG. 3 is a front elevation view thereof;

FIG. 4 is a left side elevation view thereof, the right side being a mirror image of that shown;

FIG. 5 is a bottom plan view thereof; and,

FIG. 6 is a top plan view thereof.

The broken line disclosure of a satellite dish in FIG. 1 is for illustrative purposes only and forms no part of the claimed design.
